MENDEL OSNOS, OF BERLIN, GERMANY, ASSIGNOR TO TELEFUNKEN GESELLSCHAFT FÜR DRAHTLOSE TELEGRAPHIE M. B. H., OF BERLIN, GERMANY, A CORPORATION OF GERMANY

CIRCUIT FOR HEATING THERMIONIC TUBES

Application filed June 15, 1929, Serial No. 371,251, and in Germany July 12, 1928.

This invention is directed to improvements in circuit arrangements adapted to supply heating energy for thermionic tubes, especially for radio receiving sets, in which a transformer or a choke-coil working with a highly saturated iron core is connected with the alternating current network is used to supply the filaments with certain higher harmonics or overtones suited for heating, whereas the overtones of greater length and the fundamental wave are substantially precluded from the filament. It happens that in this scheme, whenever the receiver is used with high amplification, remnants of the fundamental wave and overtones of high wave length find a path into the filament and result in a disturbing note.

Now, according to the present invention this drawback is obviated by that an inductance is connected in parallel relation to the filament, said inductance being so dimensioned that it sets up a low impedance for the fundamental wave and the longer overtones, and a high impedance for the overtones utilized for filament heating.

This inductance may further be grounded at its middle in order that the frequency of the heating potential variations may be doubled in known manner.

One embodiment in which the fundamental idea of the invention is incorporated as shown in the accompanying drawing.

The filament *a* is supplied with suitable overtones from the secondary winding of a strongly saturated transformer *t* whose primary winding is fed from an alternating current supply line by way of an arrangement precluding or shutting off higher frequencies and consisting here of a capacity *c1* and a choke coil *d*. *c2* serves for shutting off the fundamental wave and the undesirable overtones of greater wave length. In parallel relation to the filament *a* according to the present invention is an inductance *g* which is grounded in the middle. Its size is so chosen that the undesirable longer waves are substantially deviated (precluded) thereby from the filament, though the waves suited for heating are passed. If for heating the filament principally a definite

overtone is to be employed, it is recommended to tune the condenser *c2* so as to insure the passage of a maximum value of this wave, while furthermore, in parallel to the inductance *g*, there is provided another capacity *c3* which conjointly with *g* is tuned to this wave. 55

I claim:

1. In combination a space discharge device having an anode, a cathode and a control electrode, a source of alternating current for heating said cathode, a current distorting transformer connected between said source and said cathode, an impedance connected across said cathode so proportioned 60 that it offers a low impedance for frequencies equal to or less than the frequency of the alternating current from said source and a high impedance for overtones of said current source frequency suitable for filament 65 heating and a connection between the midpoint of said impedance and ground. 70

2. In combination a space discharge device having an anode, a cathode and a control electrode, a source of alternating current for heating said cathode, a current distortion means connected between said source and said cathode, a grounded impedance connected across said cathode and a tuning element in parallel with said impedance for 75 tuning said impedance to an overtone of the frequency of the current from said source. 80

3. In combination a space discharge device having an anode, a cathode and a control electrode, a source of alternating current 85 for heating said cathode, a current distortion means connected intermediate said source and said cathode, tuning means connected between said source and said distortion means, an impedance connected across 90 said cathode and a connection between the midpoint of said impedance and ground, tuning means for said impedance and means for preventing current of the fundamental frequency from passing through said 95 distortion means to said cathode. 100

4. The combination with an electron discharge device comprising a tube having therein a filamentary cathode and a cooperating anode of a strongly saturated transformer 100

connected to a source of alternating current and having its secondary connected to said cathode for energizing it, a condenser in series with said secondary and said cathode forming a circuit tuned to an overtone of the frequency of the current from said source, an inductance connected across said cathode and a connection between the midpoint of said inductance and ground, said inductance being adapted to offer a low impedance path to frequencies equal to or lower than the fundamental frequency from said source and a high impedance path for overtones desired to be utilized for energizing said filament.
